UNITED STATES PATENT OFFICE.

WILLIAM J. LONGTIN, OF PHILADELPHIA, PENNSYLVANIA, ASSIGNOR TO ALLEN HOSIERY COMPANY, OF WAYNE JUNCTION, GERMANTOWN, PHILADELPHIA, PENNSYLVANIA, A CORPORATION OF PENNSYLVANIA.

STOCKING.

1,386,266.

Specification of Letters Patent. Patented Aug. 2, 1921.

Application filed December 10, 1919. Serial No. 343,858.

To all whom it may concern:

Be it known that I, WILLIAM J. LONGTIN, a citizen of the United States, residing at Philadelphia, in the county of Philadelphia and State of Pennsylvania, have invented 5 certain new and useful Improvements in Stockings, of which the following is a specification.

Stockings consisting of a tubular continuous knitted web, the product of circular knitting machines, are provided with stout welts stitched or looped to them, and if the knee and leg portions are made of fine yarn or thread, the stockings are likely to tear, as 10 distinguished from wear, under garter strain at the knees and more especially where the knee portions are joined to the welts. Usually the yarn is changed and the tubular knee portion is made of different 15 and stronger yarn than the tubular leg portion, but this shows, and such stockings while comparatively free from tearing under garter strain present an unsightly appearance. In other cases the structure and 20 appearance are the same both at the leg and knee portions, but such stockings frequently tear under garter strain if made of fine yarn.

The principal object of the present invention is to overcome these defects or disadvantages and to provide stockings the product 25 of circular knitting machines, which present the same appearance at the leg and knee portions and which will not tear at the knees under garter strain, even when made of very 30 light yarn or thread and of very fine gage.

The invention will be claimed at the end hereof but will be first described in connection with the accompanying drawings forming part hereof and in which—

40 Figure 1, is a front view diagrammatically showing a stocking embodying features of the invention.

Fig. 2, is a schematic view of parts of a circular knitting machine to which reference is hereinafter made, and

45 Fig. 3, is an enlarged view illustrating details of construction.

1, is a stocking consisting of a tubular continuous knitted web, the product of a circular knitting machine, and fabricated of 50 even fine gage and of very light yarn or

thread, which extends to the welt 5, and is joined to it. 2, is a reinforcement, the product of splicing at the front of the knee portion of the stocking, and this reinforcement 55 while inconspicuous enough not to mar the effect of continuity throughout the leg and knee portions, extends to the welt 5, and resists the garter strain and prevents tearing. The reinforcement consists of spliced thread 60 or yarn 3, knitted in with the regular thread or yarn 4, and it is therefore well adapted to resist garter strain which tends to tear, rather than to wear, the knee portions of 65 stockings while at the same time the appearance remains substantially the same as it would be if the reinforcement were not present, because the regular yarn or thread 4, extends up to the welt.

The structure of a stocking embodying 70 features of the invention can be well understood from a description of its manufacture on circular knitting machines but in giving such a description it is not intended to limit the invention to stockings embodying it and 75 produced on any particular make or style of circular knitting machine.

The splicer cam *a*, is operated to put all the needles out of coöperation with the splicer *b*, and I provide an additional cam *c*, 80 which puts instep needles, which are the needles with longer butts or are equipped with jacks having the longer butts, back into coöperation with the splicer *b*, so that these instep needles knit splicer yarn or thread 85 and regular yarn or thread into the knee portion for as many courses below the welt, as may be desired, whereas the portion of the stocking back of the knee is knitted of the regular yarn or thread. 90

I claim:

A stocking provided with a welt and consisting of a tubular continuous knitted web of fine yarn and gage extending through the leg and knee portions, and having at the 95 front of the knee portion a reinforcement of splicing yarn extending in uniform courses with the first mentioned yarn to the welt, to, with the welt, resist garter strain and present a uniform appearance at the 100 knee and leg portions.

WILLIAM J. LONGTIN.
